[54] **METHOD FOR THE THERMAL OXIDATION OF SILICON WITH ADDED CHLORINE**[75] Inventors: **Konrad Malin**, Dettenhausen; **Dietrich Seybold**, Boeblingen, both of Germany[73] Assignee: **International Business Machines Corporation**, Armonk, N.Y.[21] Appl. No.: **596,498**[22] Filed: **July 16, 1975**

[57]

ABSTRACT

The dry thermal oxidation of silicon semiconductor material to produce an oxide layer, such as the gate oxide of a field effect transistor, is carried out by flowing oxygen over the surface of the semiconductor at an elevated temperature to form a layer of silicon oxide. The electrical properties of the layer are improved by adding chlorine to the oxygen in the form of between 0.2 and 5.0 mol % of carbon tetrachloride in order to introduce chlorine into the growing oxide layer.
